UNITED STATES PATENT OFFICE.

JAMES B. SWEENEY AND ROBERT W. LAIRD, OF ST. JOHNSBURY, VERMONT.

POWER-HAMMER.

SPECIFICATION forming part of Letters Patent No. 477,159, dated June 14, 1892.

Application filed July 21, 1891. Serial No. 400,210. (No model.)

To all whom it may concern:

Be it known that we, JAMES B. SWEENEY and ROBERT W. LAIRD, both of St. Johnsbury, in the county of Caledonia and State of Vermont, have invented a new and Improved Power-Hammer, of which the following is a full, clear, and exact description.

Our invention relates to improvements in power-hammers; and the object of our invention is to produce a power-hammer in which all the movable parts work from a common center, so as to enable the machine to be easily adjusted; which is nicely balanced, so that it may be run with little power, and consequently be worked by hand or foot power; which is provided with a counterbalanced hammer or die and has means for adjustment, so that the blow may be harder in either direction, as desired; which is provided with a substantially frictionless means for raising and lowering the hammer; which is adapted to give an elastic blow in imitation of hand-work, and which may be quickly adjusted to operate conveniently on different thicknesses of material.

To this end our invention consists in certain features of construction and combination of parts, which will be hereinafter described and claimed.

Reference is to be had to the accompanying drawings, forming a part of this specification, in which similar figures of reference indicate corresponding parts in all the views.

Figure 1 is a side elevation of the machine. Fig. 2 is a front elevation of the same. Fig. 3 is a broken plan view of the machine. Fig. 4 is a vertical longitudinal section. Fig. 5 is a broken rear elevation, partly in section; and Fig. 6 is a detail view showing the connection between the sliding hammer-head and the segment which carries it.

The machine is provided with a substantial frame 10, in the upper part of which is a transverse shaft 11, driven by a pulley 12, secured to one end and having loosely mounted on the opposite end a large disk 13, which disk has an elongated hub 13^a, extending through the machine-frame, and there will be friction enough on the hub under ordinary circumstances to hold the disk in the position in which it is placed; but to guard against any possible deviation the disk is provided with

a depending handle 14, which is firmly secured to it and which carries a common form of spring-latch 16, adapted to engage a toothed rack 15, which is arranged opposite the latch and secured to the machine-frame.

On the end of the shaft 11 which projects through the disk 13 is a crank-plate 17, having a crank-pin 18, on which is pivoted a connecting-rod 19, which rod has its opposite end pivoted to a sliding plate 20, which moves in a slideway 21, formed on the outer surface of the disk 13. The sliding plate 20 is connected with one arm 22 of a double crank 23, which crank is journaled in a lever 24, said lever being pivoted on the outer side of the disk near its upper periphery and extending tangentially across the disk and below the same to a point where it may be conveniently reached, at which point it is formed into a handle 25, having a spring-latch 16^a, adapted to engage a toothed rack 15^a and hold the lever in a desired position.

The arm 22 of the double crank is slotted near its free end, as shown at 26, so as to permit the necessary play of the pin connecting it with the sliding plate 20, and the crank is braced by a brace 24^a, pivoted to the inner side of the disk at a point opposite the upper end of the lever 24, the lower end of the brace being secured to the crank-pin. The disk is slotted, as shown at 27, to permit the necessary movement of the crank 23 and lever 24. The inner arm 28 of the double crank 23 extends rearward in a direction opposite to that of the arm 22 and connects with a depending arm 29 on the helve 30, which helve is pivoted centrally on the elongated hub 13^a of the disk 13 and has at its front end two vertically-aligning guide-pieces 31, between which is a strong flat spring 32, one end of which is rigidly secured in the front end of the helve 30 and the opposite end of which is attached to a segmental plate 33, the arms 34 of which are pivoted on the hub 13^a and shaft 11, as best shown in Figs. 4 and 5. In front of this segmental plate 33 is a vertically-sliding head 35, which moves in a slideway formed in the uprights 36 of the main frame, and this head carries the hammer or die 37. The head 35 and segmental plate 33 are connected by means of straps 38, the middle one of which is secured at its upper end to the top edge of

the head and at its lower end to the lower edge of the plate, and the other two straps have their upper ends secured to the upper edge of the plate and their lower ends secured to the bottom edge of the head. This attachment permits of a frictionless movement of the segment and head in relation to each other as the straps will alternately be wound and unwound; but instead of connecting the parts by means of straps chains, gears, or other suitable means may be employed for moving the head by the movement of the segment. Beneath the hammer 37 is the lower die or anvil 39, and the material to be operated upon is placed upon the lower die or anvil, so as to receive the blows from the hammer above.

On the rear end of the helve 30 is a counterbalancing-weight 40, which is adapted to counterbalance the hammer 37 and which may be adjusted longitudinally upon the helve 30. It will thus be seen that the hammer may be exactly balanced or the weight may be adjusted so that the hammer will move down or up with greater or less force, as desired.

The operation of the machine is as follows: The machine is first adjusted so that the hammer 37 will be normally at a desired distance above the anvil 39 by means of the handle 14. This is done by merely moving the handle backward or forward, as the movement of the handle turns the disk and causes it to move the crank 23, and thus raise or lower the rear end of the helve 30, as the case may be, and so bring the hammer into a desired position. The machine is then started and the rotary movement of the shaft 11 and crank-plate 17 causes the connecting-rod 19 and slide-plate 20 to move up and down, and the movement of the slide-plate oscillates the crank 23, and consequently tilts the helve 30, which movement of the helve moves the segmental plate 33, by means of the spring 32, and thus raises and lowers the hammer-head 35 and hammer 37, and the spring connection between the helve and segment causes an elastic blow to be struck. To change the stroke of the hammer, the lever 24 is moved backward or forward, so as to move the crank 23 into a desired position in the slot 27, and it will be readily understood that the stroke will vary, according as the crank is pushed into the slot or near the open end of the same, as the inner end of the slot is much nearer the center of the disk than the outer end. The lever 24 may be moved easily and with safety while the machine is in operation, and, as a result, the hammer may be made to deliver powerful strokes during the early stages of an operation, and the strokes may be gradually diminished in power until they may be as light as desired.

It will be noticed that the main disk, the helve, and the main operating parts of the machine are mounted on a common shaft, 65 and as a result the hammer may be made to deliver a blow in any direction by simply changing the shape of the frame and the direction of the slideway of the hammer, consequently the machine is well adapted to be 70 mounted on a tripod and operate a drill.

Having thus fully described our invention, we claim as new and desire to secure by Letters Patent—

1. A power-hammer comprising a disk arranged vertically and made adjustable around its axis, a plate held and adapted to reciprocate in a slideway arranged on a face of said disk, a driving-shaft arranged at a right angle to the disk, a helve pivoted on the latter and operating vertically, a hammer fixed on the outer end of such helve, and means for connecting the sliding plate with the helve and also with the driving-shaft, as shown and described. 75

2. In a power-hammer apparatus, the combination of a pivoted helve, a segment attached to one end of the latter and having a spring connection with it, a reciprocating hammer and guides therefor, and straps attached to the segment and hammer at their respective ends, all operating as shown and described. 80

3. In a power-hammer apparatus, the combination, with the driving-shaft, the hammer and its helve pivoted on the driving-shaft, the disk also pivoted on the shaft and thus made adjustable around it, of the lever 24, pivoted to said disk and adapted for adjustment for the purpose stated, means for locking said lever, and means for connecting it with the hammer-helve, substantially as shown and described, whereby the throw of the hammer may be regulated, as specified. 85

4. The combination, with the main frame, having a suitable driving-shaft therein, the tilting helve mounted on the shaft, and the hammer connected with and operated by the helve, of the disk mounted loosely on the shaft, the slide-plate mounted on the disk and having a crank connection with the driving-shaft, a lever pivoted on the disk, and a two-armed crank journaled in the lever and whose journal is arranged in a slot in the disk, one arm of the crank being secured to the slide-plate and the opposite arm connected with the rear end of the tilting helve, substantially as described. 90
